UNITED STATES PATENT OFFICE

CHARLES J. BROWN, OF DONORA, PENNSYLVANIA

FURNACE GAS BURNER

Application filed May 28, 1928. Serial No. 281,217.

This invention relates to burners and, while not limited thereto, relates more particularly to gaseous fuel burners for use with annealing furnaces and the like, and has for its object the provision of a novel burner construction and mounting which will prevent entirely the direct impingement of the flame from the burner upon the object to be heated.

Another object is to provide a burner which will direct the flame backward against the refractory surface of the furnace wall in which the burner is mounted, so as to heat the wall to incandescence, and thereby indirectly transmit the heat to the article or articles to be heated by radiation rather than by conduction or convection.

A further object is to provide a burner having the novel combination, construction and design of parts hereinafter described and illustrated in the accompanying drawings.

In the drawings—

Figure 1 is a transverse sectional view through an annealing furnace having the novel burners of this invention mounted therein.

Figure 2 is an enlarged sectional detail through a portion of the furnace wall and burner.

Figure 3 is an enlarged sectional view of the head end of one of the burners.

Figures 4 and 5 are views taken on the line IV—IV and V—V of Figure 2, respectively.

Referring more particularly to the drawings, the letter A designates the furnace as a whole which is composed of bottom, side, end and top walls of usual construction, except that they are provided with a series of openings 2 in which sleeves 3 are mounted to receive burners B.

The furnace walls at the inner end of each of the openings 2 are provided with concave recesses 5 adapted to receive the flame from the burners B.

The burners B are each composed of an outer air and gas mixing tube 6 spaced centrally within the sleeve 3 and provided intermediate its ends with a T-fitting 7. The tube 6 has its forward or furnace end open,

while its rear end is partially closed by a cap 8 having a centrally arranged opening into which a gas supply nozzle 9 is threaded. The cap 8 is provided with air inlet openings 10 through which primary air is drawn to be mixed with the gas from the nozzle 9. The nozzle 9 is connected to a gas supply conduit 12 which leads from a gas main 13.

A secondary air conduit 14 for air under pressure enters into the mixing tube 6 through the T-fitting 7 and extends centrally through the tube 6 to the forward or furnace end thereof. The conduit 14 is connected to an air pressure main 15.

A mushroom-shaped head member comprising a hollow stem 16 and an outwardly flaring body portion 17, is threaded onto the forward or furnace end of the secondary air conduit 14. The body portion 17 extends transversely materially beyond the gas and air mixing tube 6.

The forward or furnace side of the body portion 17 of the head is provided with a secondary air groove 18, and suitable openings 19 are provided from the groove 18 into the hollow stem portion 16 of the head through which the secondary air passes to the groove.

A deflector plate 20 is secured to and is co-extensive with the forward end of the head and is spaced from the edge thereof so as to provide an air discharge slot. The rear edge of the plate 20 is provided with a rearwardly projecting and inwardly beveled flange 21 adapted to cooperate with the peripheral edge of the body of said head to form a restricted discharge slot for the secondary air.

The curvature of the outwardly flaring body 17 of the burner head is such that the gas and air mixture flowing from the mixing tube 6 will be deflected approximately 90 degrees to the axis of the burner or substantially parallel to the face of the wall, while the restricted outlet slot for the secondary air formed by the edge of the body 17 of the burner head and the flange 21 on the plate 20, will deflect the secondary air rearwardly at an angle of approximately 60 degrees to the axis of the burner and at an angle of approximately 30 degrees to the face of the furnace wall.

In operation, the gas entering the mixing tube 6 from the nozzle 9 will aspirate primary air through the openings 10 in the cap 8, which air will mix with the gas as it flows through the tube 6. As the gas and air mixture flows out of the forward end of the tube 6, it will be ignited and, due to the novel shape of the mushroom burner head, the gas and air mixture will be deflected outwardly 5 at an angle of substantially 90 degrees or parallel with the face of the furnace wall. The secondary air, which is under pressure, will flow from the conduit 14 into the groove 18 and will be deflected back toward the furnace wall at an angle of approximately 30 degrees to the face of the wall, so as to blow the air and gas mixture back into the concave recess 5 in the wall which serves to 15 spread the flame. The secondary air furnishes the air necessary to complete combustion 20 of the gas.

Due to the fact that the burning gas and air mixture is forced rearwardly and spread over the furnace wall so as to heat the wall itself to incandescence, the wall will then transmit the heat to the annealing box or other charge to be heated by radiation rather than by conduction or convection.

While I have shown and described one 30 specific embodiment of my invention, it will be understood that I do not wish to be limited thereto since various modifications may be made without departing from the scope thereof, as defined in the appended claim.

50 I claim—

The combination with a furnace wall having a concave recess therein and an opening through said wall centrally of said recess and a sleeve mounted in said wall, of a burner 40 mounted in said sleeve and spaced from the side walls thereof, said burner comprising a gas and air mixing tube open at each end, a gas supply tube projecting into the rear end of said tube and adapted to produce an aspirating effect to draw primary air through the open rear end of the mixing tube, a secondary air tube leading from a source of air under pressure and mounted centrally within said mixing tube and terminating adjacent the 45 forward end thereof, a mushroom-like head mounted on the forward end of said secondary air tube and spaced from the forward end and side wall of said mixing tube so as to provide a passageway for the mixture of air 50 and gas from said mixing tube, said head having its rear face curved so as to deflect the air and gas mixture on a line extending approximately 90 degrees to the burner axis, and said head having its forward face 60 grooved to form an air passage, a plurality of openings from said groove to the interior of said head through which the secondary air under pressure is adapted to pass, and a baffle plate secured to the forward end of said head 65 and extending beyond said groove, said plate

having a rearwardly projecting inwardly beveled flange adapted to cooperate with the peripheral edge of said head to form a restricted outlet for the secondary air and to direct said air back on an angle against the flow of air and gas mixture from said mixing tube so as to force the burning mixture rearwardly against the furnace wall.

In testimony whereof, I have hereunto set my hand.

CHARLES J. BROWN.
